CHARLES H. FINN, OF SYRACUSE, NEW YORK.

Letters Patent No. 85,809, dated January 12, 1869.

OVEN-DOOR

The Schedule referred to in these Letters Patent and making part of the same.

To all whom it may concern:

Be it known that I, CHARLES H. FINN, of Syracuse, in the county of Onondaga, and State of New York, have invented a new and useful Improvement in Ovens; and I do hereby declare that the following is a full, clear, and exact description thereof, which will enable those skilled in the art to make and use the same, reference being had to the accompanying drawings, forming part of this specification.

The object of this invention is to provide means for determining, at all times, the temperature of baking-ovens, of cooking-stoves, and ovens in other situations; and

It consists in the construction of the oven-door to receive a thermometer, in such a manner that the bulb of the thermometer shall be inside the oven, while the scale and tube shall be on the outside of the door, or visible to the eye.

The drawing—

Figure 1 represents a side view of an oven-door, with a thermometer attached, according to my invention.

Figure 2 is a vertical cross-section of fig. 1, through the line *xx*.

Similar letters of reference indicate corresponding parts.

A is the door.

B is a bulge or protuberance on the outside of the door, with a cavity on its inner side, to receive the bulb of the thermometer.

C represents the thermometer.

As seen in fig. 2, the bulb is exposed to the heat in the oven through the orifice *d*.

The tube *e* extends upward on the outside of the door, in connection with the scale *f*, as seen in the drawing, so that the height of the mercury is at all times visible.

By the use of the thermometer, the proper temperature for baking bread, pies, meats, and other articles, can be obtained before the articles to be baked are put into the oven.

Articles are frequently spoiled in the oven for the want of proper attention to the temperature.

Too low or too high a temperature is invariably injurious.

With the thermometer arranged according to my invention, the exact degree of heat necessary for the purpose may be obtained.

Exposing certain articles to a certain temperature for a given length of time will produce a uniform result.

I claim as new, and desire to secure by Letters Patent—

The oven-door, constructed as described, with the hollow bulge *B*, communicating with the oven through the aperture *d*, and adapted to receive and protect from accident the bulb of the thermometer, whose stem extends upon the outside of the door, said bulb receiving the heat from the interior of the oven through the aperture *d*, as herein shown and described.

CHARLES H. FINN.
